UNITED STATES PATENT OFFICE.

CHARLES ANDREW HARTVIGSEN, OF SALINAS, CALIFORNIA.

WRENCH.

980,632.

Specification of Letters Patent. Patented Jan. 3, 1911.

Application filed December 10, 1909. Serial No. 532,349.

To all whom it may concern:

Be it known that I, CHARLES A. HARTVIGSEN, a citizen of the United States, and a resident of Salinas, in the county of Monterey and State of California, have invented a new and Improved Wrench, of which the following is a full, clear, and exact description.

The invention is an improvement in wrenches, more especially designed for use about automobiles, and has in view a wrench preferably of the socket type, which can be conveniently worked in places ordinarily inaccessible or of difficult working, to the wrench of conventional construction.

To this end I construct the wrench with the shank in two sections pivoted together and having means for retaining the sections at different angles of adjustment, the outer section having a socket or other equivalent wrench member journaled thereon and provided with a reversible ratchet mechanism arranged to engage the wrench member, and the other and outer section of the shank having a handle assembled therewith to extend therewith or across the outer end portion thereof.

Reference is to be had to the accompanying drawings forming a part of this specification, in which similar characters of reference indicate corresponding parts in all the views.

Figure 1 is a side elevation of a wrench constructed in accordance with my invention; Fig. 2 is a similar view showing the inner section of the shank turned at right-angles to the outer section of the shank in full lines, and arranged in alinement therewith in dotted outline; and Fig. 3 is a central longitudinal section on the line 3—3 of Fig. 1, of the wrench, with the handle passed within the outer section of the shank.

More specifically set forth, the wrench embodies in its construction a shank composed of two sections, an inner section 5 and an outer section 6, one of the sections (herein referred to as the outer section) having a bifurcation receiving the central reduced portion 7 of the inner section and pivoted thereto by a pin 8, adapting the inner section of the shank to be turned to either side of an alinement position at right-angles to the outer section of the shank. To lock the two sections of the shank in substantially any position within the limits of their adjustment, the outer section of the shank is provided with

a spring-pressed pin 9, having a rounded or tapered outer end arranged to engage any one of a number of recesses 10 of like form in the edge of the segmental portion of the outer end of the inner section of the shank. The inner section of the shank is constructed with a number of longitudinal grooves, shown to be four in number, in each of which is slidable a pawl 11, pressed inwardly by a spring 12, the latter at its outer end seating in a recess forming a continuation of the groove and bearing on the opposite end of the pawl.

A collar 13, of substantially the same external diameter as the maximum diameter of the shank sections, fits over the inner section of the shank at the inner ends of the pawl grooves or ways and prevents the pawl from being displaced laterally, as also does a cam-ring 14, revoluble on this section of the shank directly above and resting on the outer edge of the collar. The upper edge of the cam-ring has cams 16, arranged to engage in certain positions of the ring, the under or inner edges of projections 17, extending from the upper ends of the pawls, and force the pawls upwardly or outwardly against the tension of the springs, the location of the cams being such that two oppositely arranged pawls will be retracted while the other two are projected by the springs, thus causing the sets of pawls to be alternately retracted and projected by reversing the rotation of the cam-ring. The rotary movement of the cam-ring is limited on the outer section of the shank by any suitable means, such as a projection or shoulder 18 arranged on the ring, adapted to engage the shoulders or sides of adjacent pawls. Beyond the grooves or ways in which the pawls move, the outer section of the shank is extended and reduced, forming a journal 19 receiving a socket wrench member 20, the extended and reduced portion of the shank having an annular groove 21, in which engages a pin 22, passing through the wrench member and preventing the longitudinal movement of the wrench member in either direction, while permitting it to freely revolve. The upper or outer end of the wrench is constructed with teeth 23, arranged to be alternately engaged by the two sets of pawls 11, that set of pawls which is retracted by the cam-ring against the spring, being moved from the path of the shoulders or teeth. The ends of the two sets of pawls are

oppositely beveled, so that both a right-hand and left-hand ratchet mechanism for the wrench is provided.

The outer section of the shank is hollow or bored out for the greater portion of its length to receive a handle 24, the handle having an enlargement 25 at each end, and being adapted to be drawn out and turned crosswise of the shank into a slot 26 at one side, the slot extending through the upper or outer end and communicating with the bore of the shank. The complete withdrawal of the handle from the shank is prevented by a shoulder 27, arranged near the top and adapted to contact with the inner enlargement 25. When the handle is drawn out and turned to one side into the slot 26, it may be shifted to the opposite side of the shank, as shown in Figs. 1 and 2, for which purpose an opening 28 is formed in this side of the shank through which the enlargement 25 is adapted to pass. When the inner section of the shank is turned at an angle to the outer section, as shown in Fig. 2, the outer section of the shank is used as a handle, at which time the handle 24 will ordinarily be passed to its inoperative position, as shown in Fig. 3.

Having thus described my invention, I claim as new and desire to secure by Letters-Patent:

1. In a tool of the character described, a shank having a hollow portion, and a handle

adapted to be contained within the hollow portion of the shank or extend transversely and slide to either side thereof, and movable from one of said positions to the other while assembled with the shank. 35

2. In a tool of the character described, a shank having a hollow portion and provided with a slot passing through the outer end and through one side thereof, and a handle constructed to pass approximately longitudinally within the hollow portion of the shank and when withdrawn to swing to one side 45 thereof through the said slot. 40

3. In a tool of the character described, a shank having a hollow portion provided with an internal shoulder near the outer end, said shank having a slot extending through the outer end and through one side and also having an opening through the opposite side, and a handle constructed to pass within the hollow portion of the shank and into the said slot crosswise of the handle and having an enlargement at its inner end adapted to contact with the said shoulder and pass through the said opening. 50 55

In testimony whereof I have signed my name to this specification in the presence of two subscribing witnesses. 60

CHARLES ANDREW HARTVIGSEN.
